GUARD RAIL ANCHORING DEVICE

George R. Tarbox, Troy, N. Y.

Application April 18, 1933, Serial No. 666,696

3 Claims. (Cl. 189—90)

One of the objects of my invention is the provision of a novel form of anchor for guard rails which is simple to construct and effective in operation.

5 Another object is the provision of an anchor plate and an anchor bolt connected thereto, the parts being so constructed and arranged as to cause any pull that is exerted on the anchor bolt to embed the anchor plate more deeply in the soil.

10 A further object is the provision of a tension adjusting device which is interposed between the anchor bolt and the cable of the guard rail and which is simple and rugged in construction and effective in operation.

15 A further specific object of my invention is the provision of a tension adjusting device of the foregoing character which is so formed as to permit relative angular movement between the adjusting device and the anchor bolt which is connected thereto and which is provided with an arcuate groove in which a bight of a cable of the guard rail is received.

20 Other objects of my invention will appear in the specification and will be particularly pointed out in the claims.

25 My invention will best be understood by reference to the accompanying drawings in which I have illustrated a preferred embodiment there-

30 of and in which—

Fig. 1 is a side view of a guide rail anchoring and tensioning device embodying my invention;

Fig. 2 is a rear elevation of an anchor plate; 35 Fig. 3 is a side view, partially broken away and in section, of the anchor plate of Fig. 2;

Fig. 4 is a fragmentary perspective view of the rear portion of the anchor plate;

Fig. 5 is a fragmentary perspective view of an 40 end portion of the tension adjusting device;

Fig. 6 is a fragmentary perspective view of the other end of the tension adjusting device;

Fig. 7 is a fragmentary exploded perspective view illustrating the connection between the anchor bolt and the tension adjusting device for permitting relative angular movement between the two; and

Fig. 8 is a section taken on the line 8—8 of Fig. 2.

50 Like reference characters indicate like parts throughout the drawings.

Referring to the drawings and first to Figs. 1 to 4, 10 is a conventional guard rail post, the lower end of which is embedded in the ground indicated at 11. The guard rail indicated generally

5 at 12 comprises upper and lower elements 121 and 122 respectively which are supported upon the post 10 by cable fasteners 13 which may be of any desired character. The two ends of the continuous cable may be joined by a cable connector 14.

The ground anchor for the guard rail comprises an anchor plate 15 which is by preference generally triangular in form as illustrated in Fig. 2 with the lower apex or corner 16 curved forward- 10 ly at 17 as shown in Figs. 1 and 3. An anchor bolt 18 forms a substantially rigid connection with the anchor plate, and is connected thereto at a point below the center of area of the anchor plate. In the embodiment illustrated, the 15 rear side of the anchor plate is provided with a hollow boss 19 through which the anchor bolt passes and which is provided with peripherally 20 upstanding lugs 20. These lugs form a socket 21 which is polygonal in cross section, usually 25 square, in which the head 22 of the anchor bolt is received. The head of the anchor bolt conforms in cross section to the socket so that when the head of the bolt is seated therein, the anchor bolt cannot turn relatively to the anchor 30 plate. The boss 19 forms a fairly close fit around the anchor bolt 18 and the head of the bolt forms a fairly close fit in the socket so that a substantially 35 rigid connection is provided between the anchor bolt and the anchor plate.

The rear side of the anchor plate is also provided with upstanding peripheral strengthening flanges 23 and is also preferably provided with strengthening ribs 24 which are integral with the boss 19 and extend therefrom to the corners 35 of the plate. The lower end of the plate is preferably provided with a fillet 151 between the rib 24 and the plate for strengthening the lower corner which is driven into the soil and for providing 40 a rugged construction.

The upper portion of the anchor plate is comparatively wide and the surface area of that portion of the anchor plate above the connecting point of the anchor bolt is much greater than the surface area of the portion below such connection. The upper portion of the anchor plate therefore presents a comparatively large surface against the earth while the lower end which is preferably pointed presents a comparatively small surface. When a pull is exerted on the anchor bolt 18, therefore, the lower pointed end 16 of the anchor plate tends to penetrate the soil while there is no such tendency of the upper portion of the plate. The result is that a pull on the anchor bolt tends to embed the anchor plate 55

more deeply in the soil. I have found in practice that the anchor plate may conveniently be made eighteen inches wide at the upper portion and eighteen inches deep although it will, of course, be understood that any desired dimensions may be used.

A tension adjusting device, indicated generally at 25, is interposed between the anchor bolt and a bight of the cable 12. The device is preferably 10 in the form of an open frame comprising two side bars 26 joined at the one end to form a head 27 provided with an opening 28 through which the anchor bolt passes. The head 27 is preferably provided with two forwardly extending tapered 15 lips 271. The wall surrounding the opening 28 is provided with a ball socket 29 in which is received a ball member 30, preferably in the form of a semi-spherical sleeve or washer as best shown in Fig. 7 which surrounds the anchor bolt 18 and 20 permits relative angular movement between the anchor bolt and the tension adjusting device. The sleeve 30 is held to its position by a nut 31 which is received on the threaded portion 32 of the anchor bolt.

25 The opposite ends of the side bars 26 are connected by a bar 33 provided with an arcuate 30 groove 331 in which a bight 34 of the cable 12 of the guard rail is received. The cable moves quite freely in the groove formed in the tension adjusting 35 device thus equalizing the tension on the upper and lower cables. The side bars 26 preferably diverge from the head 27 to the bar 33 so that the upper edges of the anchor bolt 18, the upper side bar 26 of the tension adjusting device 35 and the upper element 121 of the cable form a substantially straight line which offers no obstruction to an object such as an automobile which engages the same. Where there is an outwardly projecting member, an automobile or 40 other object which may collide with the same, is likely to be wrecked and the guard rail itself destroyed. By making the upper edges of the anchor bolt, the tension adjusting device and the upper element of the cable as a practically continuous line, the vehicle, in case it collides therewith, rides up over the parts with minimum chance of injury either to the vehicle or to the guard rail itself.

It will be understood that the anchor bolt 18

is substantially rigid and any transverse strain which is exerted thereon is likely to form a kink. When such a kink is formed in the threaded end of the bolt, it prevents further adjustment of the nut therealong. By providing relative movement between the anchor bolt and the tension adjusting device, the parts are self-aligning and any tendency to form a bend or kink in the anchor bolt is eliminated.

Preferably, the tension adjusting device is 10 formed as one integral casting in the form of an open frame which makes the device comparatively inexpensive to manufacture and satisfactory in operation, while permitting ready access to the end of the anchor bolt which is secured thereto. 15 No machine work is required either on the anchor plate or the tension adjusting device 26 thereby eliminating labor and expense which have usually been required in devices of this character.

While I have described my invention in its preferred embodiment, it is to be understood that the words which I have used are words of description rather than of limitation and that the drawings are merely illustrative. Hence, changes within the purview of the appended claims may 25 be made without departing from the true scope and spirit of my invention.

What I claim is:

1. In a ground anchor, an anchor plate the lower portion of which is curved forwardly, and 30 an anchor bolt forming a substantially rigid connection with said plate; said connection being located below the center of area of said plate.
2. In a ground anchor, an anchor plate the lower portion of which is pointed and curved for- 35 wardly, and an anchor bolt forming a substan- tially rigid connection with said plate, the point of connection between said bolt and said plate being located below the center of area thereof.
3. In a ground anchor, an anchor plate gen- 40 erally triangular in form with one corner ar- ranged at the lower portion of said plate and curved forwardly, and an anchor bolt forming a substantially rigid connection with said plate, the point of connection between said bolt and said 45 plate being located below the center of area thereof.

GEORGE R. TARBOX,
